UNITED STATES PATENT OFFICE.

GEORGE F. ECKART, OF COVINGTON, KENTUCKY, ASSIGNOR OF ONE-HALF TO JOHN ADDISON, OF CHICAGO, ILLINOIS.

ROTARY BRUSH.

Application filed May 17, 1920. Serial No. 381,911.

To all whom it may concern:

Be it known that I, GEORGE F. ECKART, a citizen of the United States, residing at Covington, in the county of Kenton and State of Kentucky, have invented a new and useful Improvement in Rotary Brushes, of which the following is a specification.

This invention relates to rotary brushes.

It is an object of the invention to provide 10 a rotary brush which has a scraping action rather than the scratching action which is accomplished by the usual wire rotary brush. This brush is particularly intended for use in the tobacco industry for stripping the last 15 shreds of a tobacco leaf from its long central stem. For such a purpose it is essential that the leaf be removed in as large strips as possible as the value of these stripplings depends very largely upon their size.

20 Another object is to provide a brush in which the scraping elements will not have a tendency to mat or to retain therein shreds of the tobacco or other substance upon which the brush is being used.

25 These and other objects as will appear are accomplished by this invention which is fully described in the following specification and shown in the accompanying drawing in which Figure 1 is a partial longitudinal section 30 through a brush embodying the invention; Figure 2 is a similar view of the opposite end of the brush with the central sleeve in elevation, Figure 3 is a front elevation of a brush element as it comes from the dies; Figure 4 is the same but showing 35 the fingers bent at right angles; Figure 5 is a section on the line 5—5 of Figure 2; Figure 6 is similar to Figure 1 but showing a modified form of brush; Figures 7 and 8 are 40 similar to Figures 3 and 4 but showing a modified form of brush element.

In the embodiment illustrated, the rotary brush is made up upon a sleeve 10 which is secured to a shaft 11 in any suitable manner, 45 as by means of a bolt 12, so as to be readily removable therefrom. The sleeve 10 is threaded at each end to receive the nut 13 and the lock nut 14.

The sleeve 10 also has a series of external 50 grooves 15 therein, which as shown are four in number which are equally spaced about the sleeve.

A series of brush elements 16 as shown in Figures 3 and 4 have central openings which 55 permit them to be placed over the sleeve

and a series of four inwardly projecting ears 17 each of which is adapted to engage one of the spiral grooves 15 of the sleeve 10.

These brush elements are preferably made of steel which after being stamped and bent 60 into the forms shown in Figure 4 are tempered in any desired manner, so as to give them the resiliency and strength required. These brush elements are separated by means of spacers 20 which together with the ears 17 65 and the spiral grooves 15, position the spade like points 19 about the shaft in a staggered or spiral form, with spaces therebetween as shown in Figure 1.

In Figure 6 is shown a modification in 70 which bristles, preferably made of a spring metal wire, are placed between the brush elements 16 in such a way as to be supported by those elements and particularly by the spade-like tips 19. These bristles may be carried 75 in any desired way such as in openings 22 in the spacer 23. One of the great objections to the use of rotary brushes having bristles made of spring metal wire is that the bristles bend over and mash down. With these 80 bristles, however, supported and reinforced by the spring sheet metal blade, this difficulty is largely overcome and a brush is provided which will have a very much longer life.

In Figures 7 and 8 is shown a modified 85 form of brush element 16^a having straight fingers 18^a. This brush is preferable for some forms of work.

While I have shown and described but a 90 few forms of my rotary brush, it will be understood that it is capable of many modifications. Changes, therefore, in the construction and arrangement may be made 95 which do not depart from the spirit and scope of the invention as disclosed in the appended claims, in which it is my intention to cover all novelty inherent in the invention as broadly as possible in view of the prior art.

100 What I claim as new and desire to secure by Letters Patent is:

1. In a rotary brush, a sleeve, a plurality 105 of sheet metal brush elements on said sleeve each element having a series of radial fingers bent at right angles to the body of said element, spacers for said elements and means for clamping said elements longitudinally of the sleeve.

2. In a rotary brush, a sleeve, a plurality 110

of sheet metal brush elements on said sleeve, each element having a series of radial fingers bent at right angles to the body of said element, a spiral groove on said sleeve, ears 5 in said elements for engaging said groove, spacers for said elements and means for clamping said elements longitudinally of the sleeve.

3. In a rotary brush, a sleeve, a plurality 10 of sheet metal brush elements on said sleeve, each element having a series of radial fingers bent at right angles to the body of said element, spacers for said elements, means for clamping said elements longitudinally of the 15 sleeve, and radial wire brush elements between said sheet metal brush elements and reinforced thereby.

4. In a rotary brush, a sleeve, a plurality 20 of sheet metal brush elements on said sleeve, each element having a series of radial fingers having spade like tips bent at right angles to the body of said element, spacers for said elements and means for clamping said elements longitudinally of the sleeve.

25 5. A sheet metal brush element for ro-

tary brushes having a flat metal body, an opening therein and a plurality of arms radiating from said body the outer ends of which are bent at right angles to the plane of the body.

30

6. A sheet metal brush element for rotary brushes having a flat metal body, a central opening in said body, a plurality of arms radiating from said body and having pointed tips which are bent at right angles 35 to the plane of the center.

7. In a rotary brush, a plurality of sheet metal brush elements having flat bodies and openings therein, a spacer between each pair of adjacent elements, a sleeve passing 40 through said elements and spacers, each element having a series of radial fingers bent at right angles to the body of said element, each finger terminating in a spade-like tip, the tips of one element overlapping the tips 45 of the adjacent element, and means for clamping said elements longitudinally of the sleeve, whereby a notched space is formed between the tips of adjacent elements.

GEORGE F. ECKART.
